P. A. Hickey.

INVENTOR

BY *Victor J. Evans*

WITNESS:

ATTORNEY

UNITED STATES PATENT OFFICE.

ALFRED W. JESCHKE, OF BALTIMORE, MARYLAND.

SHADE BRACKET.

Application filed January 12, 1927. Serial No. 160,705.

This invention relates to a shade or curtain supporting bracket, the general object of the invention being to provide means whereby the main part of the device can be permanently fastened to the window or other frame while the shade or curtain retaining bracket is adjustably supported in said part so that it is not necessary to move the major part of the device in order to make the device fit different 10 lengths of shade rollers so that marring and scarring of the frame is prevented.

Another object of the invention is to provide latch means for holding the shade retaining bracket in adjusted position on the 15 main bracket.

This invention also consists in certain other features of construction and in the combination and arrangement of the several parts, to be hereinafter fully described, illustrated in the accompanying drawings and specifically pointed out in the appended 20 claims.

In describing my invention in detail, reference will be had to the accompanying drawings wherein like characters denote like or corresponding parts throughout the several views, and in which:—

Figure 1 is a fragmentary view of the window frame, showing one of the devices in 30 position.

Figure 2 is a section on line 3—3 of Figure 1.

Figure 3 is a perspective view of the main bracket.

Figure 4 is perspective view of a shade retaining bracket.

As shown in these views, the device comprises a main bracket A and a shade retaining bracket B, it being understood that one 40 of the brackets A is placed at each upper corner of a window or other frame, as shown in Figure 1, while one of the brackets B would be formed with a pintle receiving opening, as shown in Figure 4, and the other one 45 with a slot to receive the other pintle of a shade roller.

Each bracket A is formed of a plate 1 which has rounded ends and intermediate its ends the edges of the plate are formed with 50 extensions which are bent over twice at right-angles to provide the guides 2, the lower guide being provided with the notches 3 which form keepers for a latch member on the bracket B. The ends of the plate 1 are 55 formed with the holes 4 for receiving screws

or other fastening means which fasten the bracket to the frame.

The bracket B is provided with a flat base 5 which has its ends adapted to slide in the guides 2. A latch lever 6 is pivoted to the 60 bracket B and is adapted to engage one of the notches 3 to hold the bracket B in adjusted position on the plate 1. The lever 6 is provided with a cam part 7 at its short end and with a projection 8 on its long end, the 65 cam part 7 being adapted to engage the outer face of the plate 1 when the lever is in locking position so as to frictionally hold the lever against outward or unlocking movement. The projection 8 acts as an abutment 70 to receive the point of a tool which may be used to turn the lever to releasing position. This turning movement causes the cam part to press the plate 1 slightly away from the pivotal point of the lever to permit the cam 75 part to pass it.

From the foregoing it will be seen that I have provided simple means for enabling the brackets to be adjusted to suit different 80 lengths of shade rollers without necessitating the unscrewing or unfastening of the brackets from a window frame and putting them at a new place on the frame which not only takes time but mars the frame. With this device, the shade retaining bracket can 85 be easily and quickly adjusted to a new position in the guides 2 of the bracket A and then locked in said position by the lever 6.

It is thought from the foregoing description that the advantages and novel features 90 of my invention will be readily apparent.

I desire it to be understood that I may make changes in the construction and in the combination and arrangement of the several parts, provided that such changes fall within 95 the scope of the appended claims.

What I claim is:—

1. A device of the class described comprising a main bracket having guides thereon, one of the guides having notches therein, a roller 100 retaining bracket having a base sliding in the guides, a latch lever on the roller bracket adapted to engage one of the notches to hold the roller bracket in adjusted position, said latch lever having a cam part at its short end for frictionally engaging the base of the main bracket to hold the latch lever in locking position.

2. A device of the class described comprising a main bracket having guides thereon, one 110

of the guides having notches therein, a roller retaining bracket having a base sliding in the guides, a latch lever on the roller bracket adapted to engage one of the notches to hold the roller bracket in adjusted position, said latch lever having a cam part at its short end for frictionally engaging the base of the main

bracket to hold the latch lever in locking position and a projection at the long end of the latch lever adapted to be engaged by a ¹⁰ tool for moving the latch lever to releasing position.

In testimony whereof I affix my signature.

ALFRED W. JESCHKE.
